Manteno, Ill. 60950

Filed May 26, 1969, Ser. No. 17,365

Term of patent 14 years

Int. Cl. D9—06

U.S. Cl. D9—249

FIG. 1 is a front elevational view showing a shopping bag embodying my new design in an open position;

FIG. 2 is a bottom plan view, in closed position;

FIG. 3 is a side elevational view looking from the right of FIG. 1, in closed position;

FIG. 4 is a side elevational view looking from the right of FIG. 1, in open position;

FIG. 5 is a top plan view of the shopping bag in an open position; and

FIG. 6 is a bottom plan view thereof.

The rear is the same in appearance as the front with the outer pocket removed.

I claim:

The ornamental design for a shopping bag, substantially as shown and described.
